TRANSFER AND METHOD OF MAKING THE SAME

Application filed January 29, 1929. Serial No. 335,942.

This invention relates to transfers such as are used in transferring any desired printed or painted design to a suitable display surface, and the invention embodies a simple and economical method of manufacturing a transfer which possesses marked advantages over the usual decalcomania.

It is a particular object of the invention to provide a transfer which eliminates the necessity of soaking or moistening a decalcomania paper backing for removing the same from the printed or painted design which it is desired to apply to a display surface, this result being accomplished by making a transfer wherein the desired design is not painted or printed upon decalcomania paper as in the usual practice, but comprises simply one or more coats of paint or printing on a transparent film of a suitable carrying medium which forms a permanent part of the transferred design. The transfer is therefore simply an integral film-like structure comprising the desired design on a transparent film of a carrying medium, with said film-like structure of sufficient body to permit it being conveniently handled and applied to a desired surface without the design being first formed on a decalcomania paper backing such as must be subsequently removed from the transferred design by the use of moisture.

It is a further object of the invention to construct the film-like transfer so that the transparent coating which forms a permanent part of the transferred design and which comprises the carrying medium for the one or more coats of paint or printing will overlie the painted or printed design when the transfer to a suitable surface has been made, and will thus afford permanent protection for the transferred design.

It is a still further object of the invention to provide a suitable adhesive, when so desired, at that face of the film-like transfer which is opposite the face coated with the transparent carrying medium, so that when the face of the transferred design which has the transparent protecting coating is turned uppermost in order to protect the transferred design, the opposite face of the transferred

design which carries the adhesive will be turned toward the surface upon which the design is to appear, in order that the transfer may be securely fixed to said display surface by means of the adhesive.

It is a still further object of the invention to adapt the film-like transfer for mounting on a protecting backing for convenience in shipping and handling the transfer until such time as it is to be used, the said backing however being readily removable from the film-like transfer without the use of moisture or other delicate manipulation, so that the transfer may be easily stripped from its backing for applying to the display surface only the film-like structure which constitutes the permanently applied design.

It is a still further object of the invention to manufacture the transfer by applying to a suitable base a film of the transparent material which is to form the carrying medium for the one or more coats of paint or printing constituting the finished design, the said base and the transparent carrying medium being materials which will adhere sufficiently to prevent accidental disengagement but freely permit intentional stripping of the finished film-like transfer from the base.

After the film of the transparent carrying medium has dried, the desired design is printed or painted on this film, with preferably a final coat of paint overlying the back of the entire transfer, and a coating of a suitable adhesive may then be applied to the back of the transfer if so desired.

The resulting film-like product comprising the one or more coats of paint or printing constituting the desired design, together with the film-like coating of the transparent carrying medium, thus forms an integral transfer which is adapted for ready removal from the base in order that only the film-like structure which is to remain as the permanently applied transfer need be handled when applying the same to a desired display surface, and

in practice the film-like transfer may be left on the base until the transfer is to be used, so that the commercial product will be an integral film-like transfer readily disengageably mounted on a protecting backing, or the

transfer may be stripped from the base at the time of manufacture in order that the finished commercial product will be simply the transfer film ready for use and without a protecting backing.

The invention will be readily understood from the following description of the accompanying drawing, in which:

Fig. 1 shows the transfer on a protecting 10 backing and partially stripped therefrom.

Fig. 2 shows the transfer applied to a suitable display surface.

Fig. 3 is an enlarged vertical section 15 through the transfer mounted on its protecting backing.

Fig. 4 is a similar view showing the transfer applied to a display surface of irregular contour.

The transfer is a film-like structure comprising a transparent coating 1 of a suitable carrying medium having a desired design reversely printed or painted thereon as indicated by the printing 2 and the one or more coats of paint of contrasting color as shown 20 at 3 and 4, together with a backing coating of paint 5 preferably overlying the entire transfer, and a suitable adhesive 6 applied to the backing coating 5 if so desired. This integral film-like structure is adapted to be applied to a suitable display surface A with its backing coating 5 against the display surface and the transparent coating 1 overlying the printed or painted design which thus appears in normal or unreversed position as 25 shown in Fig. 2; and in applying the film-like transfer it is first stripped from a suitable base 7 upon which it is formed, and which may be used as a protecting backing for the transfer until such time as it is to be 30 used.

The entire film-like structure which is applied to the display surface A remains permanently fixed thereto, without the necessity of applying moisture for removing a 35 decalcomania paper backing as is the practice with ordinary transfers, and this integral film-like structure which constitutes the transferred design, and which may be handled and applied without the presence of a 40 paper backing, is thus readily flexible for following and fitting snugly against any irregularities in the display surface A as shown in Fig. 4, a result impossible to obtain with an ordinary transfer having a decalcomania paper backing such as cannot be made 45 of sufficient flexibility to lie smoothly against any other than a flat display surface.

In Fig. 1 the base 7 is shown as remaining 50 fixed to the integral film-like transfer until such time as the latter is to be used, in order to provide a protecting backing which is stripped from the transfer prior to its use, but if desired the transfer may be stripped 55 from the base 7 as soon as manufacture is completed, so that simply the film-like trans-

fer without a protecting backing constitutes the commercial product adapted for transportation and application to a display surface. With either method of use the coating of transparent carrying medium which 70 constitutes an integral part of the film-like transfer, is first applied to the base 7 when the transfer is being manufactured, and the base 7 and the coating 1 are of materials adapted to adhere sufficiently to prevent accidental displacement of the finished transfer, in order that the base may form a protecting backing constituting a part of the commercial product until such time as the transfer is to be used, but the said materials 75 which are used for base 7 and the coating 1 are such as to permit ready intentional stripping of the film-like transfer from the base without the use of moisture or other delicate manipulation, in order to provide a 80 transfer free of any extraneous backing and comprising an integral film-like structure adapted to remain as a permanent unit when fixed to a desired display surface.

In manufacturing the transfer a thin film 90 of the carrying medium 1 is applied to the base 7, and for the desired subsequent free stripping of the transfer from the base the coating 1 may be of celluloid and the surface of base 7 receiving said coating may be of 95 wax, thus insuring a freely releasable adherence permitting the film of celluloid being readily stripped from the wax. The wax surface for the base 7 may be a suitably applied wax coating on a paper or cardboard 100 foundation, or the base may be a suitably wax impregnated cardboard presenting the desired waxy surface. The celluloid is preferably in liquid form for applying a thin 105 film coating by the use of either an air brush or a squeegee, and in practice scrap celluloid, such as motion picture film trimmings may be used, with the scrap celluloid suitably reduced to liquid form, as for example by the use of acetone.

When the film of celluloid has dried on the base 7, the desired design is reversely formed on this celluloid coating, and may comprise either printing or paint, or a combination thereof with any desired contrasting 115 color effect. If any of the design is to appear in ink, that portion of the design is first reversely printed on the celluloid so as to form an ink coating such as is shown at 2, and if the design includes one or more colors, successive coats of paint 3-4 of the desired 120 different colors are then applied to the celluloid film over any printing 2, with the variously colored coats of paint occupying their respective portions of the reversed 125 design. The backing coat of paint 5 is then preferably applied so as to overlie the entire transfer and form a background for the design when it is subsequently displayed in non-reversed position, and if de-

- sired a final coating of a suitable adhesive 6 may be applied to the backing coating 5, the said adhesive being preferably any usual well-known suitably retarded glue or the 5 like such as will normally be non-sticky for convenience in handling the transfer, but which is adapted when moistened to firmly adhere to the display surface A for securing the transfer thereon.
- 10 The transparent film 1 carrying the coats of ink and painting forming the reversed design, together with the backing coat 5 and the adhesive 6 when such are employed, thus forms an integral film-like structure which 15 may be readily stripped from base 7 as a result of the contacting surfaces of wax and celluloid, and this film-like structure has a body sufficiently tough and durable to permit it being readily handled and applied to 20 the display surface A with the film 1 uppermost and the design consequently showing through the transparent film in non-reversed or normal position as shown in Fig. 4.
2. The transfer is secured to the display 25 surface by first moistening its adhesive backing 6, or if no adhesive backing is provided on the transfer the display surface A may first have a suitable adhesive such as a varnish applied thereto for engaging the back 30 of the transfer. The design when thus applied to the display surface A is protected by the overlying film of celluloid 1 which remains as a permanent part of the transferred design as shown in Fig. 4.
- 35 As a result of the ready stripping of the transfer from base 7, together with the durability of the film-like transfer even when removed from its base, the stripped transfer without any protecting backing comprises a 40 practical commercial product, but if desired the transfer may be left on the base 7 which thus forms a protecting backing until the transfer is to be used, at which time the relatively thick cardboard backing may be read- 45 ily engaged and stripped from the transfer, without the use of moisture and without the tedious manipulations involved in using a usual decalcomania having a protecting back- 50 ing which must be stripped from the surface of the decalcomania paper carrying the design, and in which usual construction the pro- 55 tecting backing and the decalcomania paper are of such thin material and so tightly ad- here as to require appreciable skill in disen- gaging the same.
- The transfer as thus described may be either opaque or transparent as determined by the use of suitable transparent or opaque paints on the transparent film coating 1, and 60 when formed of transparent paint the trans- 65 fer may thus provide a usual transparency adapted for mounting on a transparent display surface.
- The transfer by reason of its make-up com- 65 prising simply the celluloid film 1 carrying
- the desired design and without the use of decalcomania paper, is readily flexible and adapted to follow the contour of any irregular display surface such as is shown in Fig. 4, 70 and to increase the flexibility of the transfer, the celluloid film 1 and the paints and ink which are employed in making the design, may be suitably treated to insure maximum flexibility. Various ingredients for thus in- 75 creasing flexibility may be employed and are well known in the art so that no detailed description thereof is necessary, it being noted however that the celluloid when reduced to a liquid by the use of acetone may advanta- 80 geously have dibutyl phthalate castor oil and damar gum mixed therewith to insure a smooth, clearly transparent and readily flex- 85 ible film coating, and that the paints and ink for making the design may have linseed oil mixed therewith for insuring the desired flexibility, it having been found in practice that refined linseed oil treated with violet rays is particularly efficient for the purpose described.
- Such mixing of paints and the like with linseed oil treated with violet rays in order to increase their flexibility is well known in the art and therefore need not be specifically described, the process having been previous- 90 ly used in the patent leather industry where the violet ray treated linseed oil of high vis- 95 cosity is known as vacuum polymerized oil. The herein specifically described treatment of celluloid is also well known in the art, the 100 formulas which have been actually used being 10 oz. of clear celluloid scrap film dissolved in 1 gal. of commercial acetone to which 1 qt. of ethyl acetate has been added for expedit- 105 ing dissolution, and the plastisizer which is then added for desired smoothness and flexi- 110 ility comprising 5 oz. of dibutyl phthalate, 4 oz. of damar gum (lacquer damar), and 2 oz. of blown castor oil.
- The wax paper used as a base upon which 115 the transfer is to be formed, has in practice been a usual heavy kraft paper impregnated with a suitable wax and forming the product which is commercially used as a liner for vegetable crates, etc.; and in applying the 120 coating of celluloid to the wax paper base the latter is preferably extended at one edge be- 125 yond the outline of the completed design as shown by broken lines at 7^a in Fig. 1, and the film of celluloid is preferably initially ex- tended beyond the outline of the completed design but not quite to the edge 7^a of its base as shown by broken lines at 1^a, so that after the completed design has dried on its backing the uneven edges 1^a—7^a may be trimmed off along the edge 20 of the design by means of a suitable die, thereby removing those por- 130 tions of the edges of the celluloid film and its backing which may have been gradually thinned-out during the course of manufac- ture, and thus presenting an edge 20 of the

finished product which will have a maximum thickness of both the backing and the unitary structure constituting the transferable design, for convenience in readily engaging said edge of the transfer and stripping the transfer from its backing.

The application of the celluloid film to the backing 7 and the subsequent application of one or more coats of variously colored paints 10 so as to produce the desired design may be by any usual process, preferably the well-known silk screen printing process wherein stencil sheets of silk bolting cloth are successively employed for applying the respective 15 colors to the corresponding portions of the design.

I claim:

The method of making and applying a transfer, which consists in coating a waxed 20 surface of a relatively strong but flexible backing sheet with a film of celluloid, forming a design on the exposed surface of the film when the film has dried, whereby the design carrying film and backing sheet are 25 adapted for handling and transportation as a flexible unit with the design carrying film protected by the backing sheet, stripping the design carrying film from the waxed surface of the backing sheet while dry and just prior 30 to use of the design carrying film, and handling the dry design carrying film independently of any backing for mounting the same on a display surface so as to display the design with the film overlying the same and 35 remaining as a permanent part of the transfer.

In testimony whereof he has affixed his signature.

ROSS GILBERT TONGE.
